UNITED STATES PATENT OFFICE.

SEWELL M. LIPSCOMB, OF HOUSTON, TEXAS.

SCREW-HOLDING ATTACHMENT FOR SCREW DRIVERS.

Application filed September 28, 1923. Serial No. 665,305.

To all whom it may concern:

Be it known that I, SEWELL M. LIPSCOMB, citizen of the United States, residing at Houston, in the county of Harris and State 5 of Texas, have invented certain new and useful Improvements in Screw-Holding Attachments for Screw Drivers, of which the following is a specification.

This invention relates to certain new and 10 useful improvements in screw holding attachments for screw drivers by means of which screws may be effectively held with the bit of a screw driver engaged in the kerf in the head of the screw, whereby the 15 screw may be readily applied in places which are not readily accessible.

The primary object of the invention is to provide a device of the above kind, which embraces the desired qualities of simplicity 20 and durability of construction as well as efficiency in operation.

Another object of the invention is to provide an efficient form of screw holding attachment for screw drivers which may be 25 cheaply and easily manufactured and placed into use.

Other objects of the invention will appear as the nature of the same is better understood, and the invention consists in the novel 30 form, combination and arrangement of parts hereinafter more fully described, shown in the accompanying drawing and claimed.

In the drawing, wherein like reference 35 characters indicate corresponding parts throughout the several views:

Figure 1 is a side elevational view of a screw driver equipped with a screw holding attachment constructed in accordance with the present invention.

Figure 2 is an enlarged transverse sectional view, taken substantially on the line 2—2 of Figure 1, and

Figure 3 is a view similar to Figure 2, taken on the line 3—3 of Figure 1.

Referring more in detail to the drawing, 45 indicates the shank of an ordinary screw driver having a handle 6 fixed upon one end thereof and flattened and tapered at its opposite end to provide the driving bit 7 adapted to enter the kerf in the enlarged 50 head of a screw as at 8.

In accordance with the present invention, the holding attachment embodies a piece of 55 springy sheet metal comprising an elongated strip or body portion 9 having one end bent or extended at right angles and provided

with a longitudinal slot or bifurcated as at 10 to provide a pair of spaced parallel legs 11 between which the shank of the screw 8 may pass and upon which the head of the 60 screw is adapted to rest. The intermediate portion of the body 9 and the other end of the latter is provided with pairs of opposed lateral tongues 12 which so operate to provide clasps adapted to engage the shank 5 65 of the screw driver so as to hold the body 9 in position parallel with the screw driver shank and in slightly spaced relation thereto, with the bifurcated lower end of the body extending transversely beneath the bit 70 7 as shown in Figure 1.

The tongues 12 are properly curved to partially embrace the shank 5 so that the attachment is held against accidental detachment from the screw driver shank and 75 is free to move longitudinally on said shank to permit positioning of the screw 8.

A washer 13 is slidably disposed upon the screw driver shank 5 beneath the clasp composed of the upper pair of tongues 12 and 80 at a point between the two clasps, a pin 14 is extended and fastened transversely through said shank, while a helical compression spring 15 encircles the shank between the pin 14 and the washer 13 for normally 85 urging the body 9 toward the handle 6 so as to insure the yieldable retention of the screw 8 with its head kerf engaged by the bit 7.

In use, the upper end of the body 9 is 90 curved downwardly so as to slightly compress the spring 15 and move the arms 11 a sufficient distance away from the end of the bit 7 for permitting the insertion of the screw 8, between said arms 11 as shown in 95 Figure 1, whereby the body 9 is released to permit the spring 15 to raise the same and thereby bring the head of the screw into engagement with the bit 7 with the end of the latter engaged in the kerf provided in 100 the head of the screw. When the screw is thus held, the same may be applied in remote shrouded places or places which are not readily accessible and then screwed into place without danger of dropping the screw 105 or losing the same.

From the foregoing description, it is believed that the construction and operation, as well as the advantages of the invention will be readily understood and appreciated 110 by those skilled in the art.

Minor changes may be made without de-

parting from the spirit and scope of the invention as claimed.

What I claim as new is:

In combination with a screw driver having a stop member mounted upon its shaft and a spring coiled around the shaft and bearing at one end against the stop member, a screw holder attachment comprising a strip having at its edges angularly disposed resilient tongues, the said tongues being arranged in pairs, the members of the pairs being located opposite each other and at the opposite side edges of the strip, the pairs of tongues being spaced from each

other, the tongues adapted to frictionally receive the shaft between them whereby the spring and the stop member is disposed in the space between the pairs of tongues, the strips being provided at its end with a pair of spaced legs which are disposed at a right angle to the plane of the strips and which extend transversely across the end edge of the shaft of the screw driver when the attachment is applied to the said shaft.

In testimony whereof I affix my signature.

SEWELL M. LIPSCOMB.
